CLAIM

The ornamental design for hanger for a cylindrical container, as shown and described.

DESCRIPTION

FIG. 1 is a perspective view of a hanger for a cylindrical container showing my new design;

FIG. 2 is a plan view thereof, the bottom view being a mirror image thereof;

FIG. 3 is a front elevational view thereof;

FIG. 4 is a first side elevational view thereof;

FIG. 5 is the opposite side elevational view thereof; and FIG. 6 is the rear elevational view thereof.

FIG. 1

FIG. 3

FIG. 4

FIG. 2

FIG. 5

FIG. 6
